(57) **CLAIM**

The ornamental design for an electric heating radiator as shown and described.

DESCRIPTION

Figure 1.1 is a front view of a first embodiment of an electric heating radiator showing my new design;

Figure 1.2 is a top plan view thereof;

Figure 1.3 is a bottom view thereof;

Figure 1.4 is a first perspective view thereof;

Figure 1.5 is a second perspective view thereof;

Figure 1.6 is a third perspective view thereof;

Figure 1.7 is a fourth perspective view thereof;

Figure 2.1 is a front view of a second embodiment of an electric heating radiator showing my new design;

Figure 2.2 is a top plan view thereof;

Figure 2.3 is a bottom view thereof;

Figure 2.4 is a first perspective view thereof;

Figure 2.5 is a second perspective view thereof;

Figure 2.6 is a third perspective view thereof; and

Figure 2.7 is a fourth perspective view thereof.

The broken lines shown in the drawings are for the purpose of illustrating portions of the electric heating radiator and form no part of the claimed design. The broken lines showing a wire and electric plug in the drawings are included for the purpose of illustrating environment and form no part of the claimed design.
